UNITED STATES PATENT OFFICE.

ANDREW M. LOCKETT, OF NEW ORLEANS, LOUISIANA, ASSIGNOR TO A. M. LOCKETT & CO. LTD., OF NEW ORLEANS, LOUISIANA, A CORPORATION OF LOUISIANA.

LIQUID-FUEL BURNER.

Application filed April 20, 1921. Serial No. 462,806.

To all whom it may concern:

Be it known that I, ANDREW M. LOCKETT, a citizen of the United States, residing at New Orleans, in the parish of Orleans and State of Louisiana, have invented certain new and useful Improvements in Liquid-Fuel Burners, of which the following is a specification.

This invention relates to liquid fuel burners and more particularly to fuel burners or atomizers in which an oil pipe and a steam pipe enter a burner tip or head and the oil and steam emerge from said tip or head by way of separate openings or slots arranged in proximity to each other and preferably one above the other.

The objects of the invention are:

First, to construct and arrange the parts of the burner so that the same may be manufactured with the minimum of cost and number of different parts, easily and quickly assembled or taken apart for inspection and cleaning.

Second, to construct a burner of the character described in which the parts subject to wear and renewal can be made at a minimum of cost and easily and quickly replaced without the use of any special tool and skilled labor.

Third, to provide a burner in which the shape of the flame to suit the width or type of fire box or boiler, or control the amount of oil and steam hence the horse-power capacity of the burner for any particular width or shape of flame can be effected, by simply and quickly substituting different shapes and thickness of combined spreader and wear plates and without in any way altering the construction and arrangements of the main sections, castings or forgings forming the burner tip.

Fourth, to construct a burner in which it is only necessary to change two plates comprising a part of the burner tip or head, should it be necessary to modify its capacity or shape of the flame.

Fifth, other objects and advantages of the invention will appear from the detailed disclosure, mode of assembling and manner of applying the invention which will be apparent from the following description.

The invention consists of structural characteristics and relative arrangements of elements which will be hereinafter more fully

described and particularly pointed out in the appended claims.

In the accompanying one sheet of drawings, forming a part of this specification and in which similar reference characters indicate the same parts in the several figures.

Figure 1 is a longitudinal sectional view taken on line I—I of Figure 5;

Figure 2 is a transverse sectional view taken on line II—II of Figure 1;

Figure 3 is a front elevation of the burner tip or head;

Figure 4 is a side view;

Figure 5, is a plan view;

Figure 6 is a rear elevation;

Figure 7 is a plan view of one of the wearing plates;

Figure 8 is a plan view of one of the spreader plates; and

Figure 9 is a plan view of the dividing plate.

Referring to the drawings in which the preferred form of the invention is illustrated, 10 and 11 represent a pair of hollow coacting and separable sections, castings or forgings which are preferably made identical in form and construction and are adapted to have their inner and flat faces or sides 12, 12, opposed as shown. Internally screw threaded openings 13 and 14 extend from and into rear end of the sections 10 and 11, respectively, and adapted for the reception of pipes, not indicated, leading from any suitable supply of liquid fuel or oil and steam, as is common in this class of devices and need no further disclosure.

Each of the sections 10 and 11 is provided with a recess, depression or chamber 15, which extends from either of the openings 13 or 14 to the flat face or side 12 for purposes to be presently described. Each of said sections 10 and 11 is also provided with a pair of oppositely disposed openings 16, 16, adapted to receive suitable bolts 17, 17, for the purpose of firmly holding or clamping said sections 10 and 11 together and over novel and superimposed flat plates to be now described. Between the flat faces or sides 12, 12, of said sections 10 and 11 are arranged a thin and imperforate central flat dividing plate 18, (see Fig. 9), having disposed on each side thereof a flat spreader plate 19 provided with a notch or V-shaped incision 20 removed therefrom, as shown in

Figure 8, and upon each exposed flat surface of each spreader plate 19 is superimposed a similarly shaped flat wearing plate 21 (see Figure 7) having preferably a circular perforation 22. Each of said plates 18, 19 and 21 is preferably provided with but not necessarily a pair of openings 23 without the zone or passage of the fuel, steam, or air passing through the burners and which 10 register with each other and with the bolt openings 16, 16, in the sections 10 and 11, as shown in Figure 2; and when said similarly shaped plates are arranged as just described, and the bolts 17, 17 passing 15 through the sections 10 and 11 are tightened up, the plates 18, 19 and 21 are firmly and securely held in proper position between said sections 10 and 11 and with respect to each other in order to preserve the proper 20 relation between the notch or V-shaped incision 20 of plate 19 and perforation or removed portion 22 of plate 21 with respect to each other and the recesses or chambers 15.

When the sections 10 and 11 and plates 25 18, 19 and 21 are arranged as just described, it will be seen that there is formed a pair of separated and independent nozzle openings or slits 24 and 25, see Figures 1 and 3, in the forward end of the burner head or tip, and 30 each of said slits is in communication with one of the recesses or chambers 15 and a liquid fuel or steam supply opening 13 or 14.

It will be manifest that a distinct advantage is accomplished by the present construction, for the reason that the parts of the 35 burner head, namely the dividing plate 18 and wearing plates 21, which are intended to take the erosion due to the high velocity of the oil and steam passing through the 40 burner and nozzle slots 24 and 25, may be quickly and easily replaced at a cost of a few cents.

It will also be seen that by substituting spreader plates 19, with a notch 20 having 45 a smaller or larger angle than that shown in Figure 8, the shape of the flame formed by the burner head or tip can be modified so as to be smaller or larger to suit the shape of the oil furnace or fire box and efficiently 50 apply the heat to the boiler. To vary the capacity or volume of fuel or steam supply for a given angle or notch 20 in the spreader plates 10, all that is necessary is to substitute spreader plates 19 of different thicknesses, 55 which will accordingly form a larger or smaller oil and steam nozzle outlets or slits 24 and 25, without changing the shape of the flame.

From the foregoing construction and arrangements of the burner head, mode of assembling and renewing the parts thereof, which are subject to erosion or wear, it will be seen that all the objects and advantages recited in the statement of invention are 60 capable of being fully and efficiently carried

out, and while I have shown one and the preferred form of burner head, many modifications will readily suggest themselves to any one without departing from the scope of the invention as expressed in the claims. 70

What I claim is:—

1. A fuel burner comprising two coacting sections, each section having its opposed side provided with a depression and a supply opening communicating with said depression, an imperforate dividing plate, and a spreader plate provided with a V-shaped incision in its edge having the separated ends of the sides of the incision in the outer edge of the spreader plate and the meeting sides or pointed end of the incision in the inner section of the spreader plate and adjacent to and on each side of said dividing plate and registering with a depression in one of said sections, said plates being so constructed and arranged between said separable sections with the exposed sides of the spreader plates adjacent to and in contact with the separable sections as to form two independent and separated slots at one end of said sections and having independent communication with one of said depressions. 90

2. A liquid fuel burner comprising two coacting and separable sections, each section having its opposed side provided with a recess and an entrance opening communicating with said recess, an imperforate dividing plate, a spreader plate provided with an incision in its edge and adjacent to and on each side of said dividing plate, and a perforated wearing plate adjacent to the exposed side of each spreader plate, said plates, perforations and incisions being so constructed and arranged between said separable sections with the exposed sides of the wearing plate adjacent to and in contact with the separable sections as to form two independent and separated slots at one end of said sections and having independent communication with one of said recesses. 100

3. A liquid fuel burner comprising two similar coacting and separable sections, each section having its opposed side provided with a recess, and an entrance opening at one end and communicating with said recess, an imperforate dividing plate, a spreader plate provided with an incision in its edge and adjacent to and on each side of said dividing plate, and a perforated wearing plate adjacent to the exposed side of each spreader plate, said plates, perforations and incisions being so constructed and arranged between said separable sections with the exposed sides of the wearing plates adjacent to and in contact with the separable sections, and forming two separated and independent slots between and at the end of the sections opposite to that of said entrance openings. 110

4. A liquid fuel burner comprising two 120

130

similar coacting and separable sections, each section having its opposed side provided with a recess, and an entrance opening communicating with said recess, an imperforate 5 dividing plate, a spreader plate having a V-shaped portion removed from its edge and adjacent to and on each side of said dividing plate, and a wearing plate provided with a perforation adapted to communicate 10 with one of the recesses in said separable sections and register with the V-shaped portion removed from the spreader plate, and adjacent to the exposed side of each spreader plate, said plates, perforations and recessed 15 portions being so constructed and arranged between said separable sections with the exposed sides of the wearing plates adjacent to and in contact with the separable sections to form two separate and independent slots be- 20 tween and at the end of the sections.

5. A liquid fuel burner comprising two similar coacting and separable sections, each section having its opposed side provided with a recess, and an entrance opening at 25 one end and communicating with said re-

cess, an imperforate dividing plate, a spreader plate having a V-shaped portion removed from its edge and adjacent to and on each side of said dividing plate, and a wearing plate provided with a perforation 30 adapted to communicate with one of the recesses in said separable sections and register with the V-shaped portion removed from the spreader plate and adjacent to the exposed side of each spreader plate, said plates, perforations and recessed portions being so constructed and arranged between said separable sections with the exposed sides of the wearing plates adjacent to and in contact 35 with the separable sections so that the V-shaped portions removed from the spreader plates form two separated and independent slots at the end of the sections opposite to that provided with the entrance openings and each of said slots is in communication with 40 one of said recesses through the perforation of a wearing plate.

In testimony whereof I affix my signature.

ANDREW M. LOCKETT.
